UNITED STATES PATENT OFFICE.

MAX PLOTKIN, OF NEW YORK, N. Y., ASSIGNOR TO CLARA BOIS, OF BROOKLYN, NEW YORK.

STAIR STRUCTURE.

No. 811,436.

Specification of Letters Patent.

Patented Jan. 30, 1906.

Application filed March 16, 1905. Serial No. 250,431.

To all whom it may concern:

Be it known that I, MAX PLOTKIN, a citizen of the United States, and a resident of the city of New York, borough of Brooklyn, in the county of Kings and State of New York, have invented a new and Improved Stair Structure, of which the following is a full, clear, and exact description.

This invention relates to improvements in the construction of sheet-metal stairs, the object being to provide a metal stairs with a means for securing rock-asphalt, concrete, or the like on the treads in such a manner as to prevent breaking or cracking thereof.

Other objects of the invention will appear in the general description.

I will describe a stair structure embodying my invention and then point out the novel features in the appended claims.

Reference is to be had to the accompanying drawings, forming a part of this specification, in which similar characters of reference indicate corresponding parts in all the figures.

Figure 1 is a side elevation, partly in section, of a stair structure embodying my invention. Fig. 2 is a section on the line $x-x$ of Fig. 1. Fig. 3 is a section on the line $y-y$ of Fig. 1, and Fig. 4 is a sectional detail showing a modification.

Referring to the drawings, 1 designates the tread of the stair, and 2 the riser, which as here shown are formed in one single sheet of metal. At the wall side the treads and risers are bolted to angle-plates 3, which are secured to ledges 4 on a string-piece 5, bolted or otherwise secured to the wall, and at the opposite end the stairs are secured to angle-plates 6 in the form of string-pieces. At the base or lower portion of the riser 2 is a channel or reentrant portion 7, in which rock-asphalt or concrete 8 may be keyed, and the string-pieces have triangular lip portions 8^a turned against the lower portions of the risers. These reentrant portions are indicated as V-shaped; but they may be otherwise shaped without departing from the spirit of my invention. At the front of each step is a nosing, which in Fig. 1 is formed integral with the riser, the said nosing being curved out-

ward and upward, as indicated at 9, and at 50 the upper edge is a downwardly and outwardly inclined flange 10. This nosing forms a pocket to receive the outer edge of the concrete or the like, and the flange 10 firmly holds the concrete from slipping.

The steps may be secured to the string-piece 5 by means of eyebolts 11, which pass through openings in said string-piece, and bolts 12 pass through the treads or steps and also through the eyes of the bolts.

In Fig. 4 I have shown a nosing 13 formed independent of the tread or riser and of thicker metal than the nosing first described. This nosing 13 may be readily attached to any metallic stair structure.

Having thus described my invention, I claim as new and desire to secure by Letters Patent—

1. In a stair structure, a nosing forming a pocket and having a downwardly-extended 70 flange at its upper edge.

2. In a stair structure, a nosing forming a pocket and having a downwardly extended and inclined flange at its upper edge.

3. In a stair structure, a tread and a riser 75 having a reentrant at its lower portion above the tread.

4. In a stair structure, a tread and riser consisting of a single sheet of metal, the riser having a reentrant at its lower portion, and a 80 nosing formed on its upper portion.

5. In a stair structure, a tread and riser, consisting of a single sheet of metal, the riser having a reentrant at its lower portion, a nosing forming a pocket, and a downwardly-inclined flange at the upper edge of said nosing.

6. In a metal stair structure, a string-piece bent to form a ledge at its lower portion, treads and risers, angle-plates secured to the treads and risers and to said ledge, and means 90 for securing concrete or the like on the treads.

In testimony whereof I have signed my name to this specification in the presence of two subscribing witnesses.

MAX PLOTKIN.
